UNITED STATES PATENT OFFICE.

JOSEPH RAKONICK, OF ST. LOUIS, MISSOURI.

ARCH-SUPPORTING SHOE.

Application filed December 10, 1925. Serial No. 74,520.

This invention relates to improvements in shoe constructions and particularly to a shoe embodying a built-in and adjustable arch supporting structure.

5 This invention is designed particularly to improve the shoe construction shown in my prior Patent No. 1,526,608, dated February 17, 1925.

It has been found in the manufacture of 10 arch supporting shoes embodying a structure as illustrated in my prior patent above mentioned, that there is a substantial waste in material which necessarily increases the cost of production of the shoes in addition 15 to requiring special treatment of the inner sole prior to incorporating the same in the shoe structure.

In addition to the above disadvantages experienced in the manufacture of shoes of 20 this type, it has been found difficult in constructing the shoe in accordance with the above mentioned patent to produce sufficiently smooth edges at the front and rear of the primary arch supporting strip which 25 will be comfortable to the foot of the wearer of the shoe through continued use thereof.

As a result, the shoe construction of the present invention has been developed with a view of eliminating waste and simplifying 30 the several operations necessary in the structure of the shoe for reducing the cost of manufacture of the shoe and in addition providing a structure which is comfortable to the foot of the wearer throughout the 35 wearing life of the shoe.

This invention in overcoming the above mentioned disadvantages in an arch supporting shoe construction embodies the provision of a main inner sole on which is 40 mounted an arch supporting base member throughout the arch portion of the inner sole, having a portion extending upwardly along the inner side of the shoe, while a supplemental inner sole formed with an extension is superposed on top of the main inner sole and secured thereto in a suitable manner to provide a transversely extending open ended pocket throughout the arch portion of the shoe on top of said main inner sole and the base member for receiving inserts adapted to adjustably vary the height 45 of the arch of the shoe. In this way shoe constructions can be economically manufactured which incorporate an arch supporting structure for a minimum low arch and which 50 is provided with the pocket for receiving

the insert adapted to increase the height of the arch supporting portion of the shoe to fit the varying types of arches in the human foot.

With these and numerous other objects in view, the invention is more particularly pointed out in the following detailed description and claim directed to a preferred form of the invention, it being understood, however, that various changes may be made in the size, shape and relation of the parts in the manufacture of shoe constructions without departing from the spirit and scope of the invention as herein set forth.

In the drawing forming part of this application:

Figure 1 is a vertical longitudinal section through a shoe construction embodying the improvements of this invention.

Fig. 2 is a vertical transverse section through the arch portion of the shoe taken approximately on the line 2—2 of Fig. 1.

Fig. 3 is a plan view of the inner sole and arch supporting structure of the shoe in detached relation from a shoe structure, showing portions of the supplemental inner sole broken away for clearly illustrating the relation between the main inner sole, the arch supporting base member, and insert positioned within the pocket formed on the top of said main inner sole.

In the shoe construction illustrated in the drawing, 1 indicates the outer sole, 2 the upper, and 3 the main inner sole, which are all formed and united in any desired and well known manner now used in the art in the construction of a shoe.

In constructing a shoe in accordance with this improved invention for embodying an arch supporting structure therein, an arch supporting base member 4 is mounted on the main inner sole 3 on the upper face thereof prior to the incorporation of the main inner sole in the shoe construction and before the upper is secured thereto. This arch supporting base extends throughout the arch portion of the inner sole along the inside edge thereof as clearly shown in Fig. 3 and is secured to the inner sole, preferably by rows of stitching, as indicated at 5, one of which is positioned and extends along the edge portion of the main inner sole while the other secures the base member along the central portion of the main inner sole and the edge portion of said base member.

One edge portion of the base member 4

is curved as indicated at 6 and projects beyond the inside edge of the arch supporting portion of the inner sole and in the finished shoe construction extends upwardly along 5 the inside of the upper of the shoe as clearly shown in Figs. 1 and 2.

This arch supporting base member may be of greater section in the central portion thereof and is preferably of tapering section 10 towards the edge portion preferably terminating in a feather edge. This member 4 forms the main arch supporting element of the shoe construction and is adapted to provide a support for arches of minimum height 15 in a finished shoe construction.

In the construction of shoes in accordance with this invention, it has been found that what would otherwise be waste leather, can be utilized for forming these arch supporting 20 base members by shaping the same to the finished form shown in the drawing.

A supplemental insole is indicated at 7 which is co-extensive with the main inner sole 3 and the base member 4 as clearly 25 shown in the drawing, particularly Fig. 3. This supplemental inner sole is preferably constructed of relatively thin leather or other suitable material which will provide a finished inner surface in the bottom of the shoe 30 providing a comfortable surface against the foot of a wearer. This supplemental inner sole is provided throughout the inside edge of the arch portion with an extension indicated at 8 corresponding in shape to the extending portion 6 of the base member 4 and adapted to overlie the same and extend 35 upwardly throughout the arch portion of the shoe along the inside of the upper. This extension 8 is also preferably provided with 40 a feather edge in order that the edge portion will snugly fit inside of the upper and provide a smooth inner surface in the shoe.

This supplemental inner sole is attached at 45 its forward end to the forward end of the main inner sole preferably by a row of stitching as indicated at 9, which will prevent relative movement between the inner soles in the completed shoe construction. The supplemental inner sole is further secured to 50 the main inner sole along a line extending transversely of the shoe and slightly forward of the arch portion of the shoe and the base member 4, by rivets, as shown clearly at 10 in Fig. 3 or if desired, a row of stitching 55 could be used in a similar manner.

The supplemental inner sole 7 is secured to the main inner sole 3 in the above described manner before the inner sole assembly is assembled with the other part of the shoe structure. The forward end of the supplemental inner sole between the rivets 10 and the stitching 9 may be cemented to the main inner sole if desired to prevent wrinkling of one relative to the other or 60 for any other purpose such as increasing the 65

strength of the bond between the main and supplemental inner soles.

This inner sole structure is now embodied in the shoe construction and the same brought to the completed form in the usual manner known in the art and during which completion of the shoe, the nails or other securing means indicated at 11 are driven through the heel area of both the supplemental and main inner soles as well as the main outer sole for securing these parts in assembled shoe forming relation and also for securing the heel portion to the shoe. This operation of constructing the heel portion of the shoe is well known in the art and forms no part of the present invention aside from its utilization for securing the supplemental inner sole to the main inner sole.

It will be seen that in the completed shoe construction as shown in Figs. 1 and 2, an open ended pocket will be formed between the main and supplemental inner soles on top of the main inner sole and on top of the arch supporting base member 4 which extends transversely of the shoe throughout the arch portion thereof as well as the portion extending upwardly along the inside of the upper of the shoe. This pocket is adapted to receive arch supporting inserts of any desired size and shape or sections as indicated at 12, which may be positioned only on the inside portion of the shoe as shown in the drawing or if necessary, in the treatment of broken arches may extend entirely from one end of the pocket to the other throughout the portions extending along the inside of the upper as well as those portions over the main inner sole.

It has been found in the manufacture of a shoe of the character above described that the shaping operation for the arch supporting structure is substantially simplified from that disclosed in my prior patent above mentioned, which material reduces the cost of construction of the shoe in addition eliminating considerable waste and being adapted for utilizing waste material which ordinarily occurs in the construction of shoes without arch supporting structures.

A completed shoe construction according to this invention will form an arch supporting shoe adapted for what may be termed a normally low arch, so that the shoe as manufactured and sold to the trade without inserts in the pocket formed on top of the base member and main inner sole will support a foot having a normally low arch in a most comfortable manner to the wearer and in which the entire inner surface of the shoe will be smooth throughout the wearing life of the shoe.

When the retailer sells shoes constructed with this arch supporting structure incorporated therein, it will usually be necessary

- to make an examination of the customer's feet and determine the character of arch, and where the arch is higher than a normally low arch, then supplementary arch supporting inserts of a desired and predetermined shape are inserted within the transversely extending open ended pocket so as to raise the arch portion of the shoe to comfortably fit the arch of the foot of the customer.
- 5 Where a customer has broken arches or is flat footed, the arch supporting structure as built into the shoe will be sufficient to start a preliminary treatment of the foot for restoring the normal arch thereto, and in such a case shoes will be sold by the retailer to the customer and worn a determined length of time for preliminary treatment of the broken arches. Following this preliminary treatment, the customer returns to the retailer who upon making the necessary examination determines the further treatment necessary and then places inserts of any desired form or shape in the pocket on top of the main inner sole and the base member so as to increase the height of the arch portion of the shoe for further treating the foot of the wearer and for restoring the arch to its normal state. The customer then continues to wear the shoes for the further treatment and restoration of the normal arch to the foot and after the results have been successfully obtained, continues to wear the shoe for holding the arch of the foot in this normal position.
- 35 From the above description it should be appreciated that a substantially improved shoe construction has been provided incorporating an arch supporting structure in which the base member 4 forms the main base for the arch supporting structure of the shoe and for retaining the arch of the shoe

in proper shape. Further, the shoe is constructed as above described and in addition to providing a most comfortable fit on the foot of a wearer, can be manufactured at a minimum cost in view of the association of the several parts employed in constructing the shoe for eliminating and utilizing what would be otherwise waste material.

Having thus described my invention, what I claim as new is:—

A shoe having a built-in adjustable arch support, comprising an outer sole, a main inner sole, and an upper secured together in associated shoe forming relation, an arch supporting base superposed on and secured to said main inner sole and having a portion extending from the inside edge of the main inner sole throughout the arched portion of the shoe, extending upwardly along the inside of the upper for reinforcing the arch of the shoe and supporting the arch supporting structure, a supplemental inner sole superposed on the main inner sole and co-extensive therewith and having an extension overlying the extending portion of the base on the main inner sole, means securing the main and supplemental inner soles together at their forward ends, means securing said main and supplemental inner soles together along a transversely extending portion thereof at the forward portion of said extension and base, and means securing the supplemental inner sole and the main inner sole to the remaining shoe structure throughout the heel portion of the shoe, whereby a transversely extending open ended pocket is formed throughout the arch portion of the shoe on top of said base adapted to receive arch supporting inserts.

In testimony whereof I affix my signature.
JOSEPH RAKONICK.
